Inventor:

Goodrich Lightfoot

United States Patent Office.

GOODRICH LIGHTFOOT, OF ELGIN, ILLINOIS, ASSIGNOR TO HIMSELF AND
JOSEPH B. LIGHTFOOT, OF SAME PLACE.

Letters Patent No. 70,726, dated November 12, 1867.

IMPROVED BLIND-FASTENING.

The Schedule referred to in these Letters Patent and making part of the same.

TO ALL WHOM IT MAY CONCERN:

Be it known that I, GOODRICH LIGHTFOOT, of Elgin, in the county of Kane, and State of Illinois, have invented a new and useful Improvement in Fastenings for Window-Blinds; and I do hereby declare that the following is a full and exact description of the construction and operation of the same, reference being had to the annexed drawings, and to the letters of reference marked thereon, making a part of this specification, in which—

Figure 1 is a perspective view, showing the position in which the blinds are held when thrown open.

Figure 2 is a front elevation of the window-frame, with vertical section through the blinds, showing the manner of opening and closing the same.

Similar letters of reference as they occur in the several figures denote like parts in each of the drawings.

The nature of my invention relates to an improvement in a device for fastening window-blinds when opened or closed, and consists in so arranging the same that one or both may be opened or closed independent of the other, and firmly fastened in either position by means of a jointed rod, extending laterally from one blind to the other, as will be hereinafter more fully explained.

To enable others skilled in the art to make and use my invention, I will proceed to describe the same with reference to the drawings.

A and A'' are the blinds, and C the window-frame or outside casings of the same. To these casings said blinds are attached by means of hinges, which may be of any known form of construction, attached to the outward edges of said blinds. Just below the hinges which connect the same to the casings is a third hinge, e and e''. From these hinges is a rod, L, which is provided at its centre with a joint, t, said rod extending from side to side of the window, and is connected at its ends to hinges e and e'' by means of a second hinge or joint, i and i'', as shown in the drawings at n n'', figs. 1 and 2, the length of said rod being such as to extend only from one hinge to the other of said blind when the same is opened or closed, as the distance is then equal.

The objects of this arrangement are several: first, one part of the blind can be opened or closed independent of the other; second, the same can be opened or closed without raising the blind, as is the case with all heretofore known arrangements; and, third, the fastening is secure when closed.

The manner of operation is as follows: In opening the blind, the centre of rod L is moved upward, which then will admit of the blinds moving upon their hinges. The same is then readily opened or closed. The centre of rod L is then dropped to a horizontal position, and the fastening is secure.

Having thus described the nature and object of my invention, what I claim as new, and desire to secure by Letters Patent, is—

Jointed rod L, in combination with hinges e and e'', when constructed and operated substantially in the manner and for the purpose specified.

GOODRICH LIGHTFOOT.
